UNITED STATES PATENT OFFICE.

IGNATZ NEUMAN, OF NEW YORK, N. Y., ASSIGNOR TO DAVID FOX AND MORRIS BROWN, OF SAME PLACE.

CAP.

SPECIFICATION forming part of Letters Patent No. 239,187, dated March 22, 1881.

Application filed February 21, 1881. (No model.)

To all whom it may concern:

Be it known that I, IGNATZ NEUMAN, of the city, county, and State of New York, have invented a new and useful Improvement in Caps; and I do hereby declare that the following is a full, clear, and exact description of the same, reference being had to the accompanying drawings, making part of this specification.

This invention is in the nature of an improvement in caps; and the invention consists in a cap constructed with an ear and neck protector united to and at the back of the cap by a swivel, whereon the protector may turn to cover the ears and neck of the wearer or encircle the cap-body when not in use, as is more particularly hereinafter described.

In the accompanying sheet of drawings, Figure 1 represents a side view of my cap, partly in section, with protector encircling cap-body; Fig. 2, a side view of cap with protector swiveled around in position to cover the ears and neck; and Fig. 3 a view of the protector before attachment to cap-body, and showing position of swivel when protector is attached to cap.

Similar letters of reference indicate like parts in the several figures.

Winter caps provided with devices for protecting the ears and neck of the wearer are old and well known, and these protecting devices have been made in many different ways, some of them to slide up and down, others to fold up and down, and still others that are removable.

As an improvement upon caps of this description, which improvement, it is believed, possesses many advantages over any heretofore constructed, I make my cap-body A of any desirable size and shape and from any suitable material, the cap-body being, in every respect, the same as are the cap-bodies of ordinary and well-known forms. Immediately at the rear of this body A—that is, at a point at its rear equidistant from the sides *a* of the body—is formed in the cover *d* of the body an eyelet-hole, B. Between the cover *d* of the cap and its body A is placed a flat button, C, so that its flexible shank *e* will protrude through the eyelet-hole B. To this flexible shank *e* is fastened, on its inner surface and near one of its edges, a band of cloth or protector, D. This protector may be made of any desired material and of any suitable width; but it should be sufficiently long to

enable it to entirely encircle the body A of 55 the cap, and so that its ends *f* and *g* may lap over each other at the front of the cap, above the visor G, which supports them, one of them being provided with a button or catch, E, and the other end with a button-hole, F, or similar 60 device.

Now, my cap being constructed substantially as above described in this wise, when the protector is not in use it lies wholly above the lower edge, *h*, of the cap-body, encircling 65 this body, as shown in Fig. 1; but when it is intended to use the protector for the purpose of covering the ears and neck of the wearer the ends *f* *g* are disunited by unbuttoning them, and the protector D is then turned on 70 the swivel C until its previous upper edge, *k*, becomes its lower edge. The ends *f* *g* are then again united or buttoned together, when the protector assumes and retains the position shown in Fig. 2, in which position the ears and 75 neck of the wearer are fully protected from the inclemency of the weather.

To restore the protector to the position shown in Fig. 1, its ends *f* *g* are again unbuttoned and the protector turned on the swivel C until 80 its edge *k* is brought uppermost, and the ends *f* *g* being next buttoned, the protector remains in this last-named position, presenting the appearance of an ordinary band-cap.

Having thus described my invention, what I 85 claim as new, and desire to secure by Letters Patent, is—

1. A cap with an ear and neck protector secured to the back of the cap by a swivel, substantially as and for the purpose described. 90

2. In a cap with an ear and neck protector, a swivel-fastening at the back of the cap, which unites the protector to the cap-body, and buttons or other adjustable fastening devices, which unite the front ends of the protector together, substantially as and for the 95 purpose described.

3. In a cap with an ear and neck protector, the combination of the cap-body with a swivel-fastening attached to its back and a protector 100 provided with adjustable fastening devices at its ends, substantially as and for the purpose described.

IGNATZ NEUMAN.

Correction of Letters Patent No. 239,187.

It is hereby certified that Letters Patent No. 239,187, issued March 22, 1881, for an improvement in "Caps," upon the application of Ignatz Neuman, were granted improperly to David Fox and Morris Brown as assignees of the entire interest, it appearing by the assignments upon record in this Office that they were assignees of one-half interest only; that said Letters Patent should have been granted to said Ignatz Neuman jointly with said assignees; that the proper corrections have been made in the files and records of the Patent Office and are hereby made in said Letters Patent.

Signed, countersigned, and sealed this 25th day of March, A. D. 1881.

[SEAL.]

A. BELL,
Acting Secretary of the Interior.

Countersigned:

E. M. MARBLE,
Commissioner of Patents.
